United States Patent Office.

J. D. WESTCOTT, OF WATERFORD, PENNSYLVANIA.

Letters Patent No. 81,565, dated August 25, 1868.

IMPROVED PUMP-PISTON.

The Schedule referred to in these Letters Patent and making part of the same.

TO ALL WHOM IT MAY CONCERN:

Be it known that I, J. D. Westcott, of Waterford, in the county of Erie, and State of Pennsylvania, have invented a certain new and useful Improvement in Double-Acting Pump-Pistons; and I do hereby declare that the following is a full and exact description therof, reference being had to the accompanying drawings, making part of this specification, in which—

Figure 1 is a central vertical section of my improved piston, situated in the pump-cylinder.

Figure 2, a plan of the piston detached.

Figure 3, a view showing a modification.

Like letters of reference indicate corresponding parts in all the figures.

My invention consists in combining with a hollow piston-head, covering the induction-passage to the pipe, two cup-shaped shoulders or stops, as hereinafter set forth.

In the drawings, A indicates the hollow piston-rod or pipe; B B, the cup-shaped shoulders or stops secured thereon, and C the hollow piston-head, which plays between the shoulders or stops, and admits water alternately on opposite sides.

The shoulders or stops are arranged with the caps α α facing each other. The hollow interior, c, of the piston-head, is made to enclose the induction-opening, b, of the pipe at all times, and in whatever position it may be. The top and bottom of the piston-head, next the pipe, are provided with ports d d, leaving bearings f f to keep the piston in place in the pipe.

Several devices are already known in which the piston-head slides between shoulders to admit the water alternately on opposite sides. Mine differs from them in two particulars: first, the piston-head is made hollow, and encloses the induction-opening in all positions; and second, the stops B are made in the form of cups, to receive the impact of the piston-head.

The hollow piston-head enclosing the induction-opening serves as a reserve-chamber, so that at the moment of reversing the motion, the flow is more sensitive toward the pipe. It also serves, at that moment, as a check to the escape of water outward, since the impulse is lateral toward the closed sides. It furthermore admits of the opening b being cut directly in the body of the pipe, without any collar or other addition to the latter.

In addition to the above, the water has at all times a free access to opening b; therefore the piston-head requires less play between the shoulders than when the water is admitted outside the head.

The stops B B, holding a reserve of water in the cups α α , form cushions, as it were, for the impact of the piston-head, whereby the great shock and rolling are obviated, and the parts are less liable to breakage.

If desired, a bulb or secondary head may be attached to the pipe, inside the piston-head, as shown in fig. 8, in which case the induction-opening is not in the pipe but in the bulb.

What I claim as my invention, and desire to secure by Letters Patent, is—

The hollow piston-head C, enclosing the induction-opening b in all positions, and the cup-shaped stops B B, acting in connection therewith, the whole arranged as described, and operating in the manner and for the purpose specified.

In witness whereof, I have hereunto signed my name in the presence of two subscribing witnesses.

J. D. WESTCOTT.
